(57) **CLAIM**

The ornamental design for a lid as shown and described.

DESCRIPTION

FIG. 1 is a bottom, front, and right-side perspective view of a lid showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged view of FIG. 1;

FIG. 9 is an enlarged view of FIG. 6;

FIG. 10 is an enlarged view of FIG. 7;

FIG. 11 is an enlarged view of FIG. 8;

FIG. 12 is a cross-sectional view taken in the direction of line 12-12 of FIG. 7;

FIG. 13 is a cross-sectional view taken in the direction of line 13-13 of FIG. 6;

FIG. 14 is an enlarged view of FIG. 13;

FIG. 15 is a cross-sectional view of the lid in a state of use with broken line environment; and,

FIG. 16 is a cross-sectional view of the lid in another state of use with broken line environment.

The evenly dashed broken lines depict portions of the lid that form no part of the claimed design. In FIG. 12, the evenly dashed broken lines are further for defining the bound of the article and form no part of the claimed design.

In FIGS. 15 and 16, the evenly dashed broken lines are further for illustrating environment structure and form no part of the claimed design.

The dot-dashed broken lines in FIGS. 8, 10, 11, and 12 are for defining the bounds of the claimed design only and form no part of the claimed design.

The dot-dot-dashed broken lines in the article in each of FIGS. 1, 6, 7, 8 and 13 are included for the purpose of illustrating the sources of the enlarged views and form no part of the claimed design.

(Continued)

The dot-dot-dashed broken lines in each of FIGS. **8, 9, 10, 11**, and **14** are for defining the bound of the article in each of FIGS. **8, 9, 10, 11** and **14** only and form no part of the claimed design.

The broken lines connected to broken line arrows in FIGS. **6** and **7** are included for the purpose of illustrating the sources of the sectional views and form no part of the claimed design.
